Harry Bowen
ATTORNEY

UNITED STATES PATENT OFFICE

OSCAR NORLING, OF ABERDEEN, WASHINGTON

CLAMP TRUCK

Application filed April 9, 1929. Serial No. 353,705.

The invention is a clamp truck in which the clamping prongs pass within the sides of the truck to provide greater adjustment and also in which the clamping members 5 automatically lock in the end of the truck when the load is applied.

The object of the invention is to provide a clamp truck which will handle both large and small articles in which the holding 10 prongs may pass inside of the sides of the truck so that a comparatively small article may be gripped.

Another object of the invention is to provide a clamp truck in which the holding 15 prongs will automatically lock in any position.

A further object of the invention is to provide a clamp truck in which the means for locking the holding prongs is located at the 20 base of the prongs.

And a still further object of the invention is to provide a clamp truck having a comparatively large gripping range which is of a simple and economical construction.

With these ends in view the invention embodies a truck having a channel at the lower end with holding prongs slidably mounted in the channel, upwardly extending levers for operating the prongs, a foot lever for 30 operating the upwardly extending levers, and means for locking the prongs in the channels.

Other features and advantages of the invention will appear from the following description taken in connection with the drawings, wherein:—

Figure 1 is a front view of the truck with the prongs extended partially outward.

Figure 2 is a side view of the truck with part broken away showing a portion of the operating levers.

Figure 3 is a view showing the channel and base of the prong.

Figure 4 is a plan view showing the arrangement of the prong.

Figure 5 is a view showing an alternate arrangement in which a double channel is provided with the prongs at each side held 50 in different channels.

Figure 6 is a view showing a prong of an alternate design.

In the drawings the device is shown as it would be made, wherein numeral 1 indicates the truck, numeral 2 the channel, and numeral 3 the prongs.

The truck 1 may be of any suitable design or arrangement or of any type. In the design shown the truck is formed with side members 4 and 5 and cross members 6 with 60 handles 7 extending upward at the rear. It will be appreciated that the handles 7 may be omitted.

The channel 2 is located at the lower end of the side members 4 and 5 and held by a 65 strap 8 with bolts 9. The channel is formed with a groove 10 having a projection 11 at the bottom and a large projection 12 at the top extending outward slightly farther than the projection at the bottom and the inner 70 surface of the projection at the top is provided with notches 13 that may be V shaped, as shown in Figure 3, or of any other suitable shape.

It will be noted that the base 14 of the 75 prongs 3 is made so that it will slide in the slot 10 and the upper edge of the base is provided with a projection 15 which is located at the inner end and which will engage the notches 13 in the channel so that it will 80 automatically hold and lock the prong in any position. It will be observed, however, that as soon as the load is removed from the outer end of the prong the base of the prong will rest against the inner surface of the slot 10 so that the projection 15 will clear the notches 13 and permit the prong to slide in the channel, however, as soon as the load is applied to the outer end of the prong 3 the upper edge will instantly move forward so that the 90 projection 15 will fit into one of the notches 13 and positively hold and lock the prong to prevent its sliding in the channel. The outer end of the prong 3 may be provided with a lip 16 that will slide under an object to readily hold it on the truck. The bases of each of the prongs 3 are pivotally attached to levers 17 by pins 18 in slotted holes 19 and the levers are pivotally mounted on the frame of the truck by pins 20 as shown. The upper ends 100

of the levers are attached by bars 21 to a central lever 22 and the lever 22 is provided with a projecting bar 23 which is attached to a foot lever 24 through a bar 25, as shown in Figure 2. The foot lever 24 is mounted in a bracket 26 at the rear of the truck and it will be observed that as the outer end of the lever 24 is pushed downward the inner end will raise and force the bar 22 upward thereby moving the levers 17 from the position shown in full lines in Figure 1 to the position shown in dotted lines so that the prongs 3 will move inward and grip an object against which the truck may be placed. It is only necessary to press downward slightly on the projection 23 to release the prongs from the object as this will produce a motion opposite to that of clamping the object. In the design shown the truck is provided with wheels 27 which are mounted in brackets 28 at the rear, as shown in Figure 2. In the design shown in Figure 5 the channel 2 is made with two of the grooves 10 and the base of the prong at one side may be held in one of the grooves 25 with the base of the other prong in the other groove so that the bases will pass each other at the center and permit the prongs to practically close at the center and also permit them to extend outward a considerable distance at the sides. It will be observed that this arrangement will provide a very wide range of adjustment for the clamping members of the truck. In the design shown in Figure 6 the prong 3 is made with a short off-set portion between the prong and base so that the prong will be adaptable to receive merchandise of practically any type. It will also be observed that the prong may be of any other suitable type or size.

40 It will be understood that other changes may be made in the construction without departing from the spirit of the invention. One of these changes may be in the design or arrangement of the channel, another may be 45 in the use of other means for holding the channel to the truck, another may be in the use of other means for locking the prongs in the channel, and still another may be in the use of other means for adjusting the position of 50 the prongs.

The construction will be readily understood from the foregoing description. In use the device may be provided as shown and it will be observed that the truck may be 55 placed against an object and the lever 24 pressed downward so that the prongs 3 will be forced inward against the object and as soon as the object is firmly gripped the upper end of the truck is tilted slightly backward 60 so that the load on the prongs will move the projection 15 into one of the notches 13 and thereby automatically lock the position of the prongs to prevent them moving laterally in the channel. It will also be observed that 65 with the prongs arranged in this manner they

may slide inward beyond the sides of the truck and thereby be within the limits thereof so that they may grip an object smaller than the width of the truck and may also extend outward a considerable distance from the edge of the truck. By arranging the parts of the truck in this manner it is possible to provide a maximum adjustment and at the same time lock and hold the prongs at their bases instead of at some remote point.

Having thus fully described the invention what I claim as new and desire to secure by Letters Patent, is:—

In a clamp truck of the character described, a truck frame, a channel member mounted in the lower end of the frame, said channel member having a groove therethrough with notches in the groove formed in the upper outer edge of the channel member, prongs with T shaped bases slidable in the groove of the said channel and provided with projections adaptable to engage the notches in the channel, and means for operating the said prongs said bases being comparatively short and permitting the said prongs to pass within the side limits of the frame.

In testimony whereof I affix my signature.

OSCAR NORLING.
